(57) **CLAIM**

The ornamental design for a bottle for cosmetic products, as shown and described.

DESCRIPTION

1. Bottle for cosmetic products

1.1 : Perspective

1.2 : Front

1.3 : Back

1.4 : Top

1.5 : Bottom

1.6 : Left

1.7 : Right

The stipple shading in the drawings represents contours and does not illustrate surface ornamentation or decoration; the broken lines of the design are directed to the environment and are for illustrative purposes only and form no part of the claimed design.
